UNITED STATES PATENT OFFICE.

ARTHUR J. HURD, OF BARABOO, WISCONSIN.

BAG-HOLDER.

SPECIFICATION forming part of Letters Patent No. 655,236, dated August 7, 1900.

Application filed September 23, 1899. Serial No. 731,447. (No model.)

To all whom it may concern:

Be it known that I, ARTHUR J. HURD, a citizen of the United States, residing at Baraboo, in the county of Sauk and State of Wisconsin, have invented a new and useful Bag-Holder, of which the following is a specification.

The invention relates to improvements in bag-holders.

The object of the present invention is to improve the construction of bag-holders and to provide a simple, inexpensive, and efficient one adapted to distend a bag from side to side as far as possible and still afford sufficient space from front to rear to permit the bag to be filled conveniently and capable of arranging the front edge of the bag in a plane below the back of the bag to form the latter into a shield to prevent the escape of material at that point while the bag is being filled.

The invention consists in the construction and novel combination and arrangement of parts hereinafter fully described, illustrated in the accompanying drawings, and pointed out in the claim hereto appended.

In the drawings, Figure 1 is a perspective view of a bag-holder constructed in accordance with this invention, a bag being shown in dotted lines. Fig. 2 is a vertical sectional view showing the device applied to a bag and illustrating the relative arrangement of the front and back of the latter.

Like numerals of reference designate corresponding parts in both figures of the drawings.

1 designates a bag-holder constructed of stout wire or other suitable material and adapted to be arranged within the mouth of a bag 2 and to form the mouth of the said bag 40 into an opening of great width and at the same time to provide sufficient space between the front and back of the bag to enable the latter to be conveniently filled without liability of spilling the material. The opening 45 formed by the mouth of the bag is substantially segmental or arc-shaped, and the back 3 of the said bag is arranged above the front edge 4 to form a guard or shield to prevent the material from escaping at that point 50 while it is being shoveled into the bag.

The bag-holder consists of a hanger or body portion constructed of a single piece of

stout wire or other suitable material, which is doubled or bent between its ends to form a central supporting-loop 5 and it is extended 55 at opposite sides of the loop 5 to provide arms 6, which are slightly curved and which are arranged at a slight inclination when the loop is vertical, whereby the front edge of the bag is arranged below the rear edge. The arms 6 by extending substantially longitudinally of 60 the body are adapted to distend the bag from side to side as far as possible, and by slightly curving the arms to the front the necessary space from the front to the back of the bag is 65 secured. The terminals of the material of which the hanger or body portion is constructed are coiled and extended rearward to form projections 7 for engaging the bag 2. The loop 5, which has downwardly-converging 70 sides, is provided at its top with an eye 8, adapted to be arranged on a hook, nail, screw, or other suitable support for holding the device at the desired elevation, and the bag-holder may be readily removed from such support 75 when desired. The hanger or body portion is supported by a main brace 9, constructed of stout wire or other suitable material and consisting of an upper central portion 10 and inclined side portions 11. The central portion 80 10 extends across the upper portion of the loop 5 of the hanger and is connected with the sides by eyes 12, formed by coiling the material of which the brace is constructed and receiving the sides of the loop 5 at the 85 upper ends of the converging portion 13. The sides 11 of the main brace extend outward and downward from the upper portion of the loop 5 and are connected with the arms 6 at a point slightly below the bottom of the loop 90 5, and these sides 11 of the brace 9 support and stiffen the arms 6 to prevent the same from sagging or curving forward too far. The terminals of the brace 9 are coiled around the arms 6 at 14 and are extended rearward to 95 provide points or projections 15 for engaging the back of the bag. The loop 5 is further stiffened by a lower approximately-horizontal brace 16, extending across the bottom of the loop and connecting the sides at the back 100 of the bag. The brace 16, which is adapted to prevent the sides of the loop from spreading or collapsing, is connected with the same by having its terminals 17 coiled around the

said sides, as clearly illustrated in Fig. 1 of the accompanying drawings.

It will be seen that the bag-holder is exceedingly simple and inexpensive in construction, that it possesses great strength and durability, and that it is capable of holding the mouth of the bag open as wide as possible and at the same time is adapted to provide sufficient space between the front and back 5 of the said bag to enable the same to be conveniently filled. It will also be apparent that the mouth of the bag is held in substantially-segmental or arc-shaped form and that the back of the bag is caused to extend to a considerable distance above the front thereof to provide a shield or guard to prevent the material from escaping at the said back while it is being shoveled into the bag.

What is claimed is—

20 A bag-holder comprising a body portion having a vertical loop and provided with arms

6 extending downward at a slight inclination substantially longitudinally of the body and curved to the front, whereby they are adapted to distend the mouth of the bag from side to side as far as possible and form a substantially-segmental opening with the back of the bag elevated above the front to prevent the material from escaping at the back and at the sides, the lower brace connecting the sides 25 of the loop at the bottom of the same, and the upper brace extending from the upper portion of the loop to the arms 6, to stiffen them and prevent them from sagging, substantially as described.

In testimony that I claim the foregoing as my own I have hereto affixed my signature in the presence of two witnesses.

ARTHUR J. HURD.
